UNITED STATES PATENT OFFICE.

FRANZ J. WOOD, OF DES MOINES, IOWA.

MECHANISM FOR CONTROLLING AND OPERATING MOLDING MACHINES.

Application filed December 26, 1923. Serial No. 682,738.

This invention relates to improvements in molding machines employing pneumatic means for moving the mold supporting frame toward the pattern frame and having 5 means whereby the movement of the mold supporting frame from the pattern frame is adjustably retarded. I have found in actual practice that this movement should be comparatively slow at the time the patterns are being drawn from the mold, and 10 as soon as the patterns have been loosened the molding frame may be moved very rapidly, thereby eliminating considerable time in this operation.

15 It is, therefore, one of the objects of my present invention to provide improved means for controlling the mold supporting frame, whereby it will be first moved slowly away from the pattern frame and then 20 moved comparatively rapidly.

A further object of my invention is to provide in a molding machine means whereby the mold and pattern frames may be adjusted to be exactly in parallel relation with 25 each other, so that the sand will be uniformly packed within the mold.

30 My invention consists in the construction, arrangement and combination of the various parts of the device, whereby the objects contemplated are attained, as hereinafter more fully set forth, pointed out in my claims, and illustrated in the accompanying drawings, in which:

Figure 1 is a vertical, longitudinal, sectional view of the air cylinder, showing 35 in detail section the valve mechanism for controlling the action of the cylinder, and also the rapping mechanism.

Figure 2 is a detail view showing the 40 valve of said mechanism in another position of its movement.

Figure 3 is an enlarged, detail, segmental view of one of the supporting frame members, showing a portion of the controlling 45 mechanism attached thereto and in operative relation with the valve mechanism.

Figure 4 shows a segmental view of the main frame, showing the mold supporting frame and a portion of the mechanism for 50 elevating the same, and the manner in which the adjusting means for said table is applied thereto.

Figure 5 is a segmental plan view of one 55 end of the pattern frame, and a plan view of that portion of the frame illustrated in Figure 3, showing the manner in which the

improved mechanism for tilting the said pattern frame is applied thereto.

Figure 6 is a detail sectional view taken 60 on the line 6—6 of Figure 5.

Figure 7 is a vertical, sectional view of 65 my machine, the lower portion of which is taken on the line 7—7 of Figure 4; and

Figure 8 is a detail sectional view taken 70 on the line 8—8 of Figure 7.

My invention relates to improvements in molding machines, and particularly to that type of molding machines illustrated and described in my issued Patents, Number 1,451, 70 249, dated April 10, 1923, and Number 1,492,912, dated May 6, 1924.

Inasmuch as the present invention relates to improvements in molding machines illustrated and described in the above mentioned 75 patents, only fragmental sections of the molding machine are illustrated, those portions which particularly bear on my invention.

The machine in general comprises a base 10 having upright supports 12, the upper 80 ends of which have pivotally mounted between them the mold supporting frame 13. This frame is provided with means not illustrated, whereby a mold may be clamped to either its upper or lower surface, the frame being adapted to rotate to a horizontal position with either side uppermost, and when in operation to support the mold frame from its under surface. The pattern is carried by the frame 33 which is mounted in 85 such a manner as to be moved toward and from the mold frame, the pattern frame 33 being carried on a set of rollers 72, said rollers being arranged in pairs, each pair being 90 designed to carry one end of the pattern 95 frame. Each pair of rollers is mounted on an arm 70 which in turn is mounted on a rock shaft 65, said rock shaft being rotatively mounted in the base 10 in such a manner that the arm 70 may be moved from 100 a horizontal position to substantially a vertical position, and to carry therewith the roller 72 and to elevate and lower the frame 33.

The shafts 65 are each provided with an 105 operating arm 66, said arms being in substantially a common plane with the arm 70, said plane extending longitudinally through the shaft. The arms 66 are actuated by means of links 67 which extend inwardly 110 toward each other and have their adjacent ends pivotally connected to a cross head 68.

The said heads 68 are designed to travel on guide devices which comprise a plate 124 secured to the member 10 at a point vertically between the shafts 65. Adjustably secured to said plate 124 is a pair of rearwardly extending flanges 125, each of which is provided with flanges 126. Each of the flanges 126 is provided with slots 127, said slots being designed to receive bolts 128 by means of which said flanges are adjustably secured to the plate 124. The said plate 124 is also provided near its lower end with rearwardly extending lugs 129, each of which has a set screw 130, said set screw being designed to engage the outer surface of the flanges 125. The upper ends of the plate 124 are provided with similar lugs 131 having set screws 132. The flanges 125 are always arranged parallel to each other and spaced to receive the cross head member 68, said cross head being designed to carry an upwardly extending piston rod 51.

The upper end of the rod 51 is provided with a piston 49 designed to operate in a vertically arranged cylinder 47, said piston being adapted to be raised and lowered by compressed air which is controlled through mechanism hereinafter described. The cylinder 47 is mounted in a ring 133 which is pivoted in such a manner that the lower end of the cylinder is capable of a slight oscillating movement which permits the lower end of the piston rod to move laterally a slight distance. This movement is accomplished by setting one end of the flanges 125 either to the right or to the left as shown in Figure 4. When this has been done it will be seen that the upper end of the crank arms 66 will be moved slightly either to the right or to the left. This movement will cause one end of the platform 33 to be slightly elevated above the other and when at its upper limit of movement the squeezing of the sand takes place. This provides means for tilting the platform 33 for alignment with the mold frame.

For actuating the piston 49 I have provided a supply pipe 64 which is designed to convey air under pressure. For connecting the pipe 64 is a T 78, one branch of which is connected to a valve casing 54, while its other branch is connected to the upper end of a flexible hose 104. The lower end of the hose 104 is provided with a valve mechanism 105 having an upwardly extending valve stem 106 which controls the valve 107, said valve being normally held closed by means of a spring 108. The valve mechanism 105 is connected to a pipe 109 secured to the upright support 12. The opposite end of the pipe 109 is connected to a pneumatic rapper or vibrator 110 which is of the usual construction, said rapper being secured to the upright 12 at the point 111.

The valve casing 54 is provided with an

oscillating valve 55 and ports 56, 58 and 61, the valve 55 also being provided with ports 57 and 60. The port 60 is provided with a port 59. The said casing is provided with a passage communicating with the T 78 and a passage communicating with a second T 100. The T 100 is connected to the upper end of a flexible hose 103 which is provided at its lower end with a valve device 112 similar to the valve device 105 having a downwardly extending stem 113 in alinement with the stem 106. The valve 112 is secured to an exhaust pipe 114 which is also mounted on the support 12. Pivotaly mounted at one edge of the support 12 I have provided a lever 115 having a pivot 116. One end of the lever 115 is provided with an enlarged portion 117 which rests between the ends of the stem members 106 and 113 in such a manner that it may actuate either of them when the free end of the lever is elevated or lowered. The outer end of the lever 115 is provided with an adjustable weight 118 and also a laterally extending pin 119.

Pivotaly mounted to the inner face of the member 12 by means of a pivot 120 I have provided an angular lever 121 having a hook portion 122 designed to engage the pin 119 when the weighted end of the lever 115 is at its elevated position of movement and the member 117 in engagement with the valve 106. The lower end of the lever 121 is provided with a roller 123, said lever 121 being so mounted that the roller will oscillate back and forth across the path of travel of the lug 38, extended from the member 33, as the said platform 33 is elevated and lowered.

The device is in a normal position when the piston 49 and the platform 33 are at their lower position of movement, and the weighted end of the lever 115 is also in its lowered position of movement with the enlarged portion 117 engaging the valve member 113, holding the valve therein in an open position, and the valve 55 is in the position shown in Figure 1 with the port 57 in communication with the T 78 and the port 56, the last said port being provided with the pipe 52 which is connected to the lower end of the cylinder 47, and the port 60 is in communication with the T 100 and the port 58, said port 58 being provided with a pipe 53 connecting the upper end of the cylinder 49 and the port 59 is in communication with the port 61.

The T 100 is also provided with a valve casing 101 having a valve 102, said valve 102 being set to form a slow leak for the purpose hereinafter made clear.

When it is desired to elevate the platform 33, air will be caused to enter the pipe 64 and pass through the passage 57 of the valve 55 and enter the lower end of the cylinder through the pipe 52, causing the piston 47

to be elevated and with it the platform 33. The lug 38 will then be moved upwardly through the groove 39 past the roller 123 until the platform 33 has reached its upper limit of movement and the lug 38 has engaged the under side of the lever 115, moving its weighted end to an elevated position. When this has happened the squeezing of the sand has taken place, and the enlarged portion 117 of the lever 115 will have engaged the stem 106, opening the valve 107 and permitting air to enter through the pipe 104, thence through the pipe 109 to the rapper 110. This will continue until the valve 15 55 has been reversed to the position shown in Figure 2, said valve being actuated by mechanism not illustrated in the drawings. The port 57 is then in communication with the port 58 and the T 78, while the port 60 20 is in communication with the port 56 and the T 100. The pipe 52 is then placed in an exhaust position with the T 100, the valve 112 being closed. A portion of the air from the cylinder will gradually escape through 25 the passage of the valve member 101, the speed of which may be regulated by adjusting the valve 102. This will permit the piston 49 to move downwardly very slowly and also the pattern frame 33, permitting 30 the patterns to be slowly withdrawn from the mold. The lug 38 will also move downwardly and disengage the lower edge of the lever 115, the lever being locked in its elevated position by the hook 122 engaging 35 the pin 119. The lug 38 will move downwardly until it engages the roller 23 at which time the hook 122 will disengage the pin 19 and the weight 118 will move the lever downwardly, causing the member 117 40 to again engage the valve stem 113 and open the valve 112. This permits the free exhaust of the air from the lower portion of the cylinder, permitting the piston and the pattern platform to be lowered very rapidly, 45 the said piston being forced downwardly by air pressure on its top surface in addition to the weight of the parts.

Thus it will be seen that I have provided an improved means whereby the mold table 50 may be moved down gradually on its initial movement, then rapidly on the last part of its movement, and means whereby the rapper may be automatically thrown out of operation at the proper time.

55 It will be seen that I have provided means whereby the ends of the pattern frame may be elevated or lowered a slight distance to cause them to assume parallel relation with the mold longitudinally.

60 For moving the two members into parallel relation laterally, I have provided the following mechanism: It will be seen that the mold frame 13 is pivotally mounted in the upper ends of the members 12 by pivot members 22. As before described, the said frame

is adapted to be turned either side up. One end of the frame 13 is provided with a space 134 in which I have mounted a block 138 having a wedge shaped recess 136 similar to the recess 21. The block 138 is provided with flanges 137 on its outer end, designed to engage the end of the member 13, and with an inwardly extending portion 138 considerably narrower than the slot 134, the block being secured in position by means of set screws 139.

70 It will thus be seen that the pattern frame 13 may be made to assume a tilted position when rocked about the pivot centers of the said frame, and about a pivot center at right angles to the pivotal movement of the frame 33. This further provides means for adjusting the molding and pattern frames above referred to, inasmuch as it will be seen that by adjusting the set screws 139 the edge of 75 the frame 13 may be adjusted relative to the locking position of the block 38.

80 Thus it will be seen that I have provided improvements for my patents which will enable me to, first, produce a more uniform 85 packing of the sand within the mold, and second, increase the speed of the operation of the device.

I claim as my invention:

1. In a molding machine, a main frame, a 90 pattern frame mounted on said main frame, a mold table, pneumatic means for raising and lowering said mold table, said means including automatic means whereby the mold table will be moved upwardly at an accelerated speed, and automatic means for moving the mold table downwardly at an accelerated speed different from that produced by its upward movement, the first part 100 of the downward movement being comparatively slow, and the remainder of the downward movement quite rapid.

105 2. In a molding machine, a main frame, a mold supporting frame, a pattern supporting frame, a lever mechanism for raising and lowering said pattern frame, pneumatic means for operating said lever mechanism, means for causing said pneumatic means to be moved in one direction at a uniform speed and in the opposite direction at varied speeds, said lever mechanism being adapted 110 to move the pattern frame at accelerated speeds relative to the speed of said pneumatic means.

115 3. In a molding machine, a main frame, a pattern frame mounted on said main frame, a mold table, and means for elevating and lowering said mold table, comprising an air chamber, a piston, a compound lever device operatively connecting said piston and said mold table, means for supplying air to said piston to move it upwardly at a uniform speed, and arranged to permit the piston to lower first at a comparatively slow 120 speed, and then at a comparatively rapid 125 130

speed, the said compound lever devices being designed to impart an accelerated speed to the platform relative to the speed of said piston.

5 4. In a molding machine, a main frame, a pattern frame mounted on said main frame, a mold table, means for elevating and lowering said mold table, comprising an air chamber, a piston, a compound lever device 10 operatively connecting said piston and said mold table, means for supplying air to said piston to move it upwardly at a uniform speed, and arranged to permit the piston to lower first at a comparatively slow speed, 15 and then at a comparatively rapid speed, the said compound lever devices being designed to impart an accelerated speed to the platform relative to the speed of said piston, and means for rapping said mold table at 20 the time the mold table has reached its upper limit of movement and is being moved downwardly at its slow speed.

5 5. In a molding machine, a main frame, a pattern frame mounted on said main frame, a mold table, means for elevating and lowering said mold table, comprising an air chamber, a piston, a compound lever device 25 operatively connecting said piston and said mold table, means for supplying air to said piston to move it upwardly at a uniform speed, and arranged to permit the piston to lower first at a comparatively slow speed, and then at a comparatively rapid speed, the 30 said compound lever devices being designed to impart an accelerated speed to the platform relative to the speed of said piston, means for rapping said mold table at the 35 time the mold table has reached its upper limit of movement and is being moved downwardly at its slow speed, and means for automatically throwing said rapping mechanism 40

into and out of operative relation with the aforesaid mechanism.

6. In a molding machine, a main frame, a mold frame, a pattern frame adapted to move toward and from said mold frame, means for moving said pattern frame comprising a pair of parallel rock shafts, a pair of rock arms for each of said shafts, one of the rock arms of each of said shafts being designed to engage the lower surface of said pattern frame and to elevate the same by swinging from a horizontal to a vertical position, the other pair of said rock arms being provided with inwardly extending links having their inner ends connected to a cross head, means for guiding said cross head to travel in a substantially vertical path, and means for elevating and lowering said cross head. 50 55 60

7. In a molding machine, a main frame, a mold frame, a pattern frame adapted to move toward and from said mold frame, means for moving said pattern frame comprising a pair of parallel rock shafts, a pair of rock arms for each of said shafts, one of the rock arms of each of said shafts being designed to engage the lower surface of said pattern frame and to elevate the same by swinging from a horizontal to a vertical position, the other pair of said rock arms being provided with inwardly extending links having their inner ends connected to a cross head, means for guiding said cross head to travel in a substantially vertical path, means 75 80 85 for elevating and lowering said cross head, and means for shifting one end of said guiding means from the true vertical position for the purpose of alining said pattern frame with said mold frame. 75

Des Moines, Iowa, November 22, 1925.

FRANZ J. WOOD.
